UNITED STATES PATENT OFFICE.

JOSEPH CHLEBORAD, OF OMAHA, NEBRASKA.

WINDOW.

No. 925,294.

Specification of Letters Patent.

Patented June 15, 1909.

Application filed May 9, 1908. Serial No. 431,891.

To all whom it may concern:

Be it known that I, JOSEPH CHLEBORAD, a citizen of the United States, and a resident of Omaha, in the county of Douglas and State of 5 Nebraska, have invented certain new and useful Improvements in Windows, of which the following is a specification.

My invention is an improvement in windows and consists in certain novel constructions and combinations of parts hereinafter 10 described and claimed.

Referring to the drawings forming a part hereof, Figure 1 is a vertical section through a window constructed in accordance with 15 my improvement. Fig. 2 is a front view of a sash. Fig. 3 is a transverse section of a part of the casement, and Fig. 4 is a section of a portion of the casement on the line 4—4 of Fig. 3. Fig. 5 is a vertical section through a 20 modified form. Fig. 6 is a similar view of another modification. Fig. 7 is a similar view of another modification. Fig. 8 is a view of the rear sash shown in Figs. 5 and 6. Fig. 9 is a similar view of the front sash, and 25 Fig. 10 is a detail of the spring connecting the two sections of the sash shown in Fig. 8.

The present embodiment of my invention comprises a circular casement 1 provided on its upper face with annular grooves 2, separated from each other by a parting strip 3, the frame being provided on its front face with an annular flange 4. The outer wall of the outer groove is provided with a rubber cushion 5, against which the frame of the 30 upper sash to be presently described rests, and the inner wall of the rear groove is provided with a similar cushion against which the frame of the lower sash rests. The rear cushion 5 is connected with an annular rim 6, which rim forms the outer wall of the groove, and is retained in place by an annular ring or stop 7, the ring 7 being secured to the casement by screws 8. Each of the sashes 40 comprises an annular frame 9, provided with a diametrical center rail 10, the upper face of the rail and that portion of the sash above the rail in the upper sash, and the lower face of the rail and that portion of the sash below the rail in the lower sash being grooved to receive the glass 11, as shown in Fig. 1, and the width of the frame is greater above the rail than below, to form a proper setting for the glass. The sashes are rotatable in the casement, the bottom of the annular grooves 2 being provided at suitable intervals with 45 friction rollers 12, journaled in the casement,

and arranged with their peripheral surface projecting slightly above the bottom of the grooves. Each of the sashes is provided with a lock comprising a pin 13 slidably mounted in the frame, and adapted to engage openings 14 in the window frame, the pin being provided with a handle 15 for convenience in manipulating the same and being retained in locked position by a spring 16. 60 At the center of the cross bars 10, a bearing 17 is provided which is adapted to receive a pin 18, for locking the center rails of the sash together, and the bottom of the grooves at the lower part of the frame are in communication with a channel 19, leading to the front of the frame whereby to provide drainage for the grooves. 70

It will be evident from the description, that by releasing the locking pin 14, either of the sashes may be rotated in its groove, whereby to open the top or the bottom of the window, or to reverse the position of the sashes. 75

In assembling the window the casement 80 being in position, the front or upper sash is put in place, then the parting strip is inserted and the lower sash is put in place. The inside rim is then placed in position, and the stop 7 is secured in place by screws 8. 85

It will be understood that ordinarily both sashes are precisely alike, and that the casement and the sash are made of any suitable material either wood or metal.

In the form shown in Fig. 5, the parting strip is dispensed with, and the front sash comprises a hemispherical frame 20, provided with a diametrical center rail 21, in which the glass 22 is arranged, and the said sash is fixed in the frame, the upper half of the inner face 90 of the casement being cut-away as at 23, for receiving the sash. This cut-away portion extends rearwardly the entire thickness of the sash and becomes annular to form a groove 24, in which is received a ring 25 having on its inner face an annular rib 26, the said ring and the front sash being secured in place by a ring 27 secured to the casement by screws 28. The rear sash consists of a split ring 29, provided on its peripheral face with a 100 groove 30, in which is received the rib 26, and the ends of the rings are normally spaced apart from each other as at 31, the said ends being connected by a spring 32, whose ends extend into casings 33 secured to the respective ends of the ring. 105

It will be evident from the description that

by pressing the casings 33 toward each other against the resistance of the spring, the ring will be contracted whereby to easily rotate in the casement, to open or close the window.

5 In the construction just described, the upper sash may be provided with the center rail 21 as shown in Fig. 6, or the center rail may be dispensed with as shown in Fig. 5, and if desired the rear sash may be provided 10 with a center rail 34, as shown in Fig. 6, or said rail may be dispensed with as shown in Fig. 5. A pin 35 may be used to lock the center rails together as shown in Fig. 6, or the said pin may be omitted as shown in 15 Fig. 7.

In Figs. 5 and 6, the outer groove being omitted, at the bottom of the casement, the passage 19 shown in Figs. 1 and 7 is also omitted.

20 In Fig. 7, each of the sashes is hemispherical and the upper sash 36, is rigid in the casement, the peripheral surface thereof having an annular recess 37 at its rear portion, which recess registers with an annular groove 38 in the lower part of the casement.

25 The inner or lower sash 39, is provided on the edge of its circular portion with a tongue 40 moving in the groove 38 and the recess 37 and the sashes are secured in place by a ring 30 41 secured to the casement by screws 42.

I claim:

1. A window comprising a circular casement, a fixed upper sash, a ring secured with-

in the casement behind the upper sash and provided on its inner face with an annular 35 rib, a lower sash comprising a split ring provided on its peripheral surface with a groove for receiving the rib, and a spring normally retaining the ends of the ring in spaced relation whereby to retain the rib in the groove. 40

2. A window comprising a circular casement, a fixed upper sash, a lower sash comprising a split ring rotatably mounted in the casement, and a spring normally retaining the ends of the ring in spaced relation 45 whereby to retain the outer face of the sash in engagement with the casement.

3. A window comprising a circular casement having on its inner face an annular groove, said groove being of greater width at 50 its upper half than at its lower half, toward the front of the casement, a semi-circular casement, arranged in the outer portion of the upper half of the groove, a ring arranged in the annular groove behind the semi-circular sash and provided on its inner face with an annular rib, a split ring having in its outer 55 face an annular groove for receiving the rib, said ring having its ends spaced apart when the rib is engaged with the groove, and a 60 spring arranged between said ends to retain the ring in such position.

JOSEPH CHLEBORAD.
